UNITED STATES PATENT OFFICE.

FLORIAN K. PYLICK, OF CLEVELAND, OHIO.

DESIGN FOR A HEAT-RADIATING DRUM.

SPECIFICATION forming part of Design No. 29,585, dated November 1, 1898.

Application filed September 28, 1898. Serial No. 692,137. Term of patent 7 years.

To all whom it may concern:

Be it known that I, FLORIAN K. PYLICK, a citizen of the United States, residing at Cleveland, in the county of Cuyahoga and State of Ohio, have invented and produced a new and original Design for Heat-Radiating Drums for Stoves, of which the following is a specification, reference being had to the accompanying drawing, forming part thereof.

5. The single figure in the accompanying drawing is a front elevation of a heat-radiating drum, showing my new design.

As shown in the drawing, the leading or material feature of my design consists of a series of parallel tubes A and vertical tubes B, disposed or arranged as shown, the said tubes A and B being substantially circular in cross-section. The vertical tubes B are disposed

and arranged some distance from each end of tubes A, thus giving a checkered or staggered appearance to the design as a whole. The ends of tubes A are cone-shaped, as seen at C. The top and lower tubes A are intersected centrally between tubes B by tubes D and E, respectively, the said tubes projecting outward and the lower tube E being slightly flaring, as seen at e.

Having described my invention, what I claim as new, and desire to secure by Letters Patent, is—

The design for a heat-radiating drum, as herein shown and described.

FLORIAN K. PYLICK.
